United States Patent Office

Des. 179,045
Patented Oct. 23, 1956

179,045

APPLIQUE

Alfred Weil, New York, N. Y., assignor to Bernard Workman, Inc., New York, N. Y.

Application June 15, 1955, Serial No. 36,531

Term of patent 14 years

(Cl. D3—9)

Fig. 1

Fig. 2

Fig. 3

Fig. 1 is a top plan view of an applique, showing my new design.

Fig. 2 is a front view of Fig. 1, and

Fig. 3 is a side view of Fig. 1.

The dominant features of the design are represented in the drawings in full lines.

I claim:

The design for an applique, substantially as shown and described.
